UNITED STATES PATENT OFFICE.

WILLIAM GOODROW, OF CHICAGO, ILLINOIS.

ADJUSTABLE CORNICE.

1,304,678.

Specification of Letters Patent. Patented May 27, 1919.

Application filed January 5, 1918. Serial No. 210,466.

To all whom it may concern:

Be it known that I, WILLIAM GOODROW, a citizen of the United States, residing at Chicago, in the county of Cook and State 5 of Illinois, have invented certain new and useful Improvements in Adjustable Cornices, of which the following is a specification.

This invention relates to an adjustable 10 cornice especially adapted for mounting over windows and like places where it may serve, in an ornamental capacity, to conceal rods, cords or other supports for draperies, hangings, etc., and as a support for valance.

15 Cornices of the kind herein contemplated are frequently mounted over the upper trim surrounding the inner side of a window, and are usually made to order according to the widths of the windows where they are to be 20 used. The present cornice, however, which is capable of lengthwise adjustment, may be supplied in standard stock lengths and be fitted to the window at the time it is set up in place. In this manner my cornice 25 may be quickly and easily adjusted to conform to any width of window within the limits of its size, permitting its removal, if desired, without requiring any special skill or labor in fitting it in place.

30 In order that the several parts of my cornice may be maintained in rigid relation at all times and be possessed with a desirable degree of strength, I have provided several novel and improved features which 35 do not, however, affect measurably the simplicity of its construction, the cost of its manufacture, or its ornamental appearance. As will be more fully hereinafter seen, from the specification and claims, my 40 invention includes other objects and uses as well.

In the drawings: Figure 1 is a perspective view of the present cornice mounted over an ordinary window. Fig. 2 is a plan view of 45 the same. Fig. 3 is a rear view thereof, and Figs. 4 and 5 are enlarged transverse sections taken on lines 4—4 and 5—5 respectively of Fig. 2.

Three major elements constitute the present cornice—a center-piece A and two end sections B and C, each slidably connected with the center-piece. Arranged in right angular relation with the sections B and C are end pieces 6 and 7, respectively, which 55 serve to space the elements A, B and C out from the window trim or molding 8 to

which the cornice may conveniently be secured as by means of hook and eye connections 9.

Each of the sections B and C on its front 60 face is formed with certain ornamental configurations consisting, in part at least, of a plurality of beads or ridges, designated as 10, extending lengthwise of the cornice, a suggested profile being clearly shown in 65 Figs. 4 and 5. The rear face of the centerpiece A is likewise configured to correspond, in a measure at least, with the profile of the sections B and C, that is, it is formed with grooves or channels 11 having a complementary 70 relation to the beads or ridges 10. It is obvious, of course, that the presence of beads or ridges on any of the cornice elements will result in the formation of grooves or channels immediately adjacent 75 thereto, and vice versa, so that it will be understood these terms are used in a relative sense.

Upon the rear face of the center-piece I have arranged in the center thereof a vertical 80 block 12 (see Figs. 2, 3 and 5) whose rear side substantially alines with the rear faces of the sections B and C when in operative relation with the center-piece. This block, which may be conveniently secured in 85 place with screws 13, carries a channel bar 14 whose flanges 15 lie within slots 16 formed in the block, a screw 17 being employed to fasten the bar upon the block. The facing sides of the bar flanges 15 are 90 preferably obliquely disposed, tapering toward each other in the direction of the bar body. Upon the rear face of each section B and C parallel channels 18 are provided (see Figs. 3 and 4) each having an obliquely 95 inclined side conforming to the slope of the facing sides of the bar flanges 15 and adapted to partly receive therein the said flanges. I prefer also to countersink slightly the surface 19 of the sections B and 100 C lying between the channels 18, so that if pressure be brought to bear upon the channel bar, tending to force its flanges farther into the channels 18, the surfaces of the sections B and C lying between the said 105 channels will not engage with the bar body to thereby interfere with such movement.

When the cornice elements are in operative relation, the proximate ends of the sections B and C will lie one on either side of the 110 block 12 and both behind the center-piece A and in front of the channel bar 14. By

means of the center-piece on the front side and the channel bar on the rear side, these end sections B and C are maintained in straight line relation. The complementary 5 beads and grooves formed on the three cornice elements not only assist in preserving this relation, but prevent these parts from sagging as well. It will be seen, therefore, that the several cornice elements are rigidly connected by the means which I have 10 described. This connection, however, is one that permits the end sections B and C to be slidingly withdrawn from the center-piece for a considerable distance so that the length 15 of the cornice may be thereby altered as required. During such adjusting movements, the screw 17 is preferably loosened, so as to reduce the friction of the channel bar upon the sections B and C. When the proper adjustment has been made, however, the screw 20 should be tightened to force the bar flanges tightly into the channels 18. By so doing, the parts of the cornice will be locked against further adjusting movement, and it may 25 thereafter be handled without special care.

The present cornice, it will be noted, is simple in construction and operation. To lock the parts in any given position of adjustment, it is necessary merely to tighten 30 a single screw. The pressure exerted by the bar flanges within the channels 18 results in forces being applied laterally owing to the oblique relation of the engaging surfaces, and this affords a secure means for maintaining the parts in their proper relation. Owing to the inter-engagement of the complementary elements which make up the profile of the cornice, the several parts are effectively secured against sagging of any 35 kind.

I claim:

1. A cornice consisting, in combination, of a center-piece, a block secured to the rear face of the center-piece, a channel bar carried by the block extending parallel to the center-piece, end sections slidingly arranged between the center-piece and bar, one on each side of the block, the end sections on their rear sides being each provided with 45 obliquely disposed channels within which the flanges of the channel bar may lie, and means for pressing the bar flanges against the oblique sides of the channels to exert a lateral pressure against the end sections for holding 50 them in a fixed position of adjustment relative to the center-piece, substantially as described.

2. A cornice consisting, in combination, of a center-piece provided with a longitudinally extending groove on its rear face, a block 60 secured to the rear face of the center-piece, a bar carried by the block extending parallel to the center-piece, end sections slidingly arranged between the center-piece and bar, one on each side of the block, and an 65 ornamental profile on the front face of each end section including a bead arranged in complementary relation to the groove on the center-piece, the bead lying within the groove to preserve the parts in alined relation, substantially as described.

3. A cornice consisting, in combination, of a center-piece provided with a longitudinally extending groove on its rear face, a block secured to the rear face of the center-piece, 75 a bar carried by the block extending parallel to the center-piece, end sections slidingly arranged between the center-piece and bar, one on each side of the block, an ornamental profile on the front face of each end section including a bead arranged in complementary relation to the groove on the center-piece, the bead lying within the groove to preserve the parts in alined relation, substantially as described.

4. A cornice consisting, in combination, of two end sections each formed with a definite profile on its front face, a center-piece arranged to lie in front of the proximate ends of the end sections and having its rear face profiled in partial conformity with the front profile of the end sections, whereby the 95 projecting parts of the rear face of the center-piece will lie within corresponding recessed parts on the front face of the end sections, and means carried by the center-piece engaging with the rear side of the end sections for holding the same against the rear side of the center-piece, the engaging profile elements serving to hold the several parts in alined relation, substantially as described.

5. A cornice consisting, in combination, of two end sections each formed with a definite profile on its front face, a center-piece arranged to lie in front of the proximate ends of the end sections and having its rear face profiled in partial conformity with the front profile of the end sections, whereby the 95 projecting parts of the rear face of the center-piece will lie within corresponding recessed parts on the front face of the end sections, and means carried by the center-piece engaging with the rear side of the end sections for holding the same against the rear side of the center-piece, the engaging profile elements serving to hold the several parts in alined relation, substantially as described.

WILLIAM GOODROW.
